METHOD OF MANUFACTURING SLIDING CLASP FASTENERS

Josef Kuna, London, England, assignor of one-half to Brevetia Limited, London, England, a British company

Application June 29, 1940, Serial No. 343,060
In Great Britain January 22, 1940

10 Claims. (Cl. 18—59)

The present invention relates to sliding clasp fasteners, the fastening members and preferably also stop members of which are made of non-metallic material such as Celluloid or other cellulosic material, Bakelite and analogous materials, now commonly embraced in the term "plastics."

An object of this invention is to provide an improved sliding clasp fastener of this kind.

An object of this invention is to provide an improved method of making such fasteners, and particularly of assembling the non-metallic members on their flexible supports.

Still another object is to provide improved non-metallic stop members for sliding clasp fasteners.

A further object of the invention is to prevent any damage to the flexible supports during the manufacture of the sliding clasp fasteners.

Other objects and advantages of the invention will become apparent from the subjoined detailed description taken in conjunction with the accompanying drawings in which—

Fig. 1 is a view of one form of a complete sliding clasp fastener embodying the invention.

Figs. 2, 3 and 4 are perspective views illustrating steps in the manufacture of the fastener of Fig. 1.

Fig. 5 is a view in greater detail of one of the fastening members of the fastener of Fig. 1.

Fig. 6 is a perspective view of part of a stop member at the open, upper, end of the sliding clasp fastener of Fig. 1.

Figs. 7 and 8 are perspective views showing both sides of part of the stop member at the closed, lower, end of the fastener of Fig. 1.

Figs. 9 and 10 are more detailed views respectively of the upper and lower end of the fastener of Fig. 1 in closed position.

Figs. 11 to 20 are views corresponding respectively to those of Figs. 1 to 10, of another embodiment.

Referring first to Figs. 1 to 10, the sliding clasp fastener illustrated comprises a pair of similar tapes 10 or other flexible supports each having attached to it a series of fastening members denoted generally by 13 spaced longitudinally along the edge 14 of the tape, which edge is shown as being beaded or thickened. A pair of stop members denoted generally by 16 are provided at the open, upper, end of the fastener, one attached to each tape 10, and a single stop member 17 is attached to both tapes at the closed, lower, end of the fastener. The member 13 are provided with coupling projections 18 and corresponding recesses 19 (shown more clearly in Fig. 5), the

projection 18 of a member 13 on one tape being adapted to be brought into and out of interlocking engagement with a recess 19 of an adjacent member 13 on the other tape by means 5 of a slider 20 of conventional construction to close and open the fastener in known manner. The fastening members 13 and the stop members 16 and 17 are made of non-metallic material such as Celluloid or other cellulosic material (e. g. 10 cellulose acetate), Bakelite or analogous plastic material.

Difficulties have been experienced hitherto in attaching to the tape of a sliding clasp fastener members made of non-metallic material of the 15 character just mentioned. Securing such members by glue or other adhesive necessitates extreme care to avoid the tapes becoming soiled during the gluing process. Resort to casting, moulding, or press-forming the members on the 20 tapes in situ has the defect that the choice of shape for the coupling projections and recesses is restricted owing to the fact that the recesses have to correspond in shape to the projections and have to be so shaped that the mould or the 25 like used for forming the members can be easily removed notwithstanding the fact that the members are closely spaced on the tape.

According to the present invention, each member consists of complementary parts, generally two, one part being cast, moulded, or press-formed in situ on the tape, while the other part is formed independently and subsequently joined to the first part, for example by means of an adhesive, the coupling projections and recesses 35 being provided substantially on the second part.

Fig. 2 illustrates the tape 10 on to which are cast in situ parts 21. Each part 21 surrounds the beaded edge 14 of the tape 10 and has a recess 22 and a lug 23. In order to enable a plurality of parts 21 to be formed simultaneously around the edge of the tape 10 at the correct distance from each other, each lug 23 has an extension 24 connected to a rod-like member 25 ascertaining the distance between the parts 21 and enabling all the parts 21 to be formed by means of a common mould. It will be seen that the parts 21 are not provided with coupling members.

Fig. 3 shows a plurality of parts 26 having 50 lugs 27 adapted to fit into the recesses 22 of the parts 21. The parts 26 are connected together to form a strip of parts by means of extensions 28 connected to a rod-like member 30 which ascertains the correct distance between the parts 26. Each part 26 has a coupling projection 18

and a corresponding recess 19. The recesses 22 and the corresponding lugs 27 are dovetailed.

As illustrated in Figs. 4 and 5, the parts 26 are joined to the parts 21 by inserting the lugs 21 into the recesses 22. The parts 26 are held in position by the lugs 23 which also close on one side the recesses 32 (see Fig. 5). The parts 26 are adhesively secured to the parts 21 by any suitable means such as acetone. After the parts 26 have been joined to the parts 21 the lugs 24 together with the rod 25 and the lugs 28 together with the rods 30 are cut off.

The stop members 16 consist also of two parts, one part being a part 21, the other part 33 having the shape illustrated in Fig. 6. It possesses a lug 34 adapted to fit into the recess 22 of the part 21 and a recess 35 accommodating the lug 23 of the part 21. It will be appreciated that in the manufacture of a stringer, the part 21 for the stop member 16 may be formed simultaneously with the parts 21 for the fastening members proper, and the part 33 of the stop member may be formed simultaneously with the parts 27 of the fastening members. The part 33 is joined and adhesively secured to its corresponding part 21.

Fig. 9 shows the upper part of the fastener in its closed position, the slider being omitted.

The stop member 17 at the closed end of the fastener is made by joining a bridge-like member 36 (see Figs. 7, 8 and 10) to parts 42 and 43 which are in shape identical with the parts 21. Each member 36 has lugs 40 and 41 adapted to fit into recesses 44 and 45 of the parts 42 and 43. The bridge member 36 is joined and adhesively secured to the parts 42 and 43. Figs. 11 to 20 illustrate a second embodiment of the sliding clasp fastener according to this invention. Whereas each fastening member of the sliding clasp fastener according to Figs. 1-10 has one coupling recess and a corresponding coupling projection, each fastening member 50 of the sliding clasp fastener according to Figs. 11 to 20 has two coupling recesses 53 and 54 and corresponding coupling projections 51 and 52 extending into opposite directions.

In the manufacture of this sliding clasp fastener, parts 55 are formed in situ on the tape 11 around its beaded edge 15 (see Fig. 12), each part 55 having a stepped recess 56 and a lug 57 provided with an extension 60 joined to a connecting rod 61. Again, the parts 55 do not possess any coupling projections and recesses.

Fig. 13 shows a strip of parts 62 each having two projections 51 and 52 and two recesses 53 and 54. Extensions 63 connect each part 62 to a rod 64. Each part 62 is stepped as indicated at 65 so as to fit into the recess 56 of a part 55. As will be more clearly appreciated from Figs. 14 and 15, the parts 62 are joined to the parts 55 and adhesively secured thereto by any suitable means, the lugs 57 closing at one side the recesses 53 and 54 of the parts 62. Subsequently the lugs 60 and 63, together with the rods 61 and 64 are cut off.

Again, the stop members 66 at the open end of the fastener are formed of two parts 55 and 67 (see Figs. 16 and 19).

The stop member 67 at the closed end of the fastener comprises three parts, two parts being parts 55, connected together by a bridge member 70 (see Figs. 17, 18 and 20).

While I have shown and described in this specification two embodiments which my invention may assume in practice, it should be clearly understood that this description is only for the pur-

pose of illustration and that other forms may occur to those skilled in the art.

What I claim is:

1. In the manufacture of sliding clasp fasteners, the steps of forming a part of one fastener element in situ on an edge of a flexible fastener tape, forming a complementary part of said member independently of said first part, and securing said second part with said first part to form one fastener element on the fastener tape.

2. In the manufacture of sliding clasp fasteners the steps of casting a part of a fastener member on an edge of a flexible support of the fastener, forming a complementary part of said member independently of said first part, applying said second part to said first part and securing adhesively said second part to said first part, thereby forming a complete fastening member.

3. In the manufacture of sliding clasp fasteners the steps of casting simultaneously and in spaced relationship to one another a plurality of parts of fastening members on an edge of a flexible support of the fastener, forming independently of said plurality of parts a strip consisting of a plurality of complementary parts of said members, said second parts being interconnected with one another in the same spaced relationship, applying said second parts to said first parts, securing adhesively respective parts together and removing the connection between the parts.

4. In the manufacture of sliding clasp fasteners the steps of casting on an edge of a flexible support of the fastener a plurality of parts of fastening members, forming on each part a recess, a lug, an extension on each lug and a rod-like member connecting said extensions to ascertain a desired spaced relationship between said parts and to facilitate the casting of said parts by a common mould, forming independently of said parts a strip of complementary parts, a lug on each of said second parts adapted to fit into said recess of one of said first parts, and means for connecting said second parts together and ascertaining the desired spaced relationship between said second parts, inserting and securing adhesively said lugs of said second parts in said recesses of said first parts, and removing said extensions, said rod-like member and said connecting means.

5. In the manufacture of sliding clasp fasteners, the steps of forming a series of fastener member parts in situ and in spaced relationship on the edge of a flexible stringer tape, forming connected spaced fastener member parts complementary to the series of fastener member parts, securing the complementary parts to the respective first parts to form complete fastener members and removing the connection between the complementary parts.

6. In the manufacture of sliding clasp fasteners, the steps of forming a connected series of fastener member parts in situ and in spaced relationship on the edge of a flexible stringer tape, forming connected spaced fastener member parts complementary to the series of fastener member parts, securing the complementary parts to the respective first parts to form complete fastener members and removing the connections between the respective complementary parts and the first parts, whereby the complete fastener elements are supported on the edge of the flexible stringer tape.

7. In the manufacture of sliding clasp fasteners, the steps of forming in spaced relationship on the edge of a flexible stringer tape a series of

parts of incomplete fastener members provided with tape gripping jaws, forming a series of parts of an incomplete fastener member complementary to the first named series of parts and, connected in spaced relationship, each provided with an interlocking projection and recess structure, securing the complementary parts to the first named parts to form a complete fastener member and removing the connection between the complementary parts.

8. In the manufacture of sliding clasp fasteners, the steps of forming in spaced relationship on the edge of a flexible stringer tape an integrally connected series of parts of incomplete fastener members provided with tape gripping jaws, forming an integrally connected series of parts of an incomplete fastener member complementary to the first named series of parts and, connected in spaced relationship, each provided with an interlocking projection and recess structure, securing the complementary parts to the first named parts to form a complete fastener member and removing the connection between the respective complementary parts and the respective first named parts, whereby the complete fastener elements are supported on the edge of the flexible stringer tape.

9. In the manufacture of sliding clasp fasteners, the steps of forming along a flexible stringer tape a series of spaced similar fastener element sections, forming a series of spaced similar fastener element sections complementary to the first named fastener element sections in spaced relationship on a support of material identical with that of the elements, interconnecting the respective complementary fastener element sections with the first named fastener element sections and separating the support from the completed fastener elements formed of the connected element sections.
10. In the manufacture of sliding clasp fasteners, the steps of mounting a series of similar segments of slide fastener elements in spaced relationship along a flexible stringer tape, mounting a series of similar segments of fastener elements complementary to the first named segments along a support, interconnecting the respective series of segments and complementary segments en masse, to form a series of completed slide fastener elements, and separating from the completed slide fastener elements the support for the series of complementary segments.

JOSEF KUNA.
